INSTRUMENT BOARD LIGHT

John M. Roper, Washington, D. C.

Application August 13, 1936, Serial No. 95,837

2 Claims. (Cl. 240—8.16)

(Granted under the act of March 3, 1883, as
amended April 30, 1928; 370 O. G. 757)

This invention relates to an instrument board light and has for an object to provide an improved lighting arrangement especially applicable to the lighting of the instrument board and cockpit of an airplane, and at the same time the lighting of a chart board located in the center of the cockpit. A further object of this invention is to provide a non-reflecting instrument board lighting arrangement which will be non-glaring and hence make the instruments easier to read and also which will not reflect any image of the instrument board to the adjacent windshield.

A further object of this invention is to provide a light fixture that may be mounted to direct a light on the instrument board and at the same time have a controllable shutter for directing a light ray into the cockpit onto a chart board located therein.

With the foregoing and other objects in view, the invention consists in the construction, combination and arrangement of parts, as will be described more fully hereafter.

In the drawing:

Fig. 1 is an elevational view of a board with the instrument lights of this invention mounted in operative position along the sides of the cockpit of an airplane;

Fig. 2 is an elevational view of the instrument light fixture, per se;

Fig. 3 is a sectional view through Fig. 2, and Fig. 4 is a section on line 4—4 of Fig. 3.

There is shown at 10 the cockpit of an airplane having a chart board located at 11 and the customary instrument board located at 12, the pilot seat being located as at 13. Secured along the opposite sides 14 of the cockpit 10 is a bracket 15 having a threaded clamp bolt 16 mounted for universal adjustment therein by means of the ball nut 17 and socket nut 18 which clamp on opposite sides of a hemisphere 19 formed in the bracket 15 and having a slot 20 through which the clamp bolt 16 extends.

The clamp bolt 16 is provided with a clamp eye 21 through which extends a socket 22, the socket 22 being preferably of the type described in my companion case Serial No. 94,182, filed August 4, 1936. This socket includes stranded conducting wires 23 extending through the cable 24 and the cable conduit 25 to the conductor terminal 26 located within the insulating collar 27, the stranded wires 23 being soldered to the terminal 26 as at 28. The socket 22 is provided with an inturned flange 29, while the conductor 26 is provided with a ferrule 30 having an out-turned

flange 31 against which a compression spring 32 is located, the other end of the compression spring 32 resting against the inside of the in-turned flange 29 to thus yieldably urge the conductor terminal 26 against the lamp contact 33 in the base 34 of a lamp 35, the lamp base 34 being provided with pins 36 for yieldably holding it in bayonet slots 37 formed in the socket 22. The electric socket described forms the subject matter of and is claimed in the copending application above referred to.

Mounted on the outside of the socket 22 is cylindrical sleeve 38 which is of such a diameter that it will snugly fit thereabout. This sleeve 38 is provided with a depressed neck 39 which acts as a base for lens 40, which is held in position therein by a split ring 41 fitting into an internal groove 42. This lens 40 is preferably in the form of a Nicol prism so that the light rays 43 passing therethrough will be polarized. The Nicol prism is mounted for axial rotation to adjust the relative plane of polarization. A plurality of oblong slots 44 in the side of the sleeve 38 permit light rays 46 to pass therethrough from the lamp 35. A shutter sleeve 47 and a cooperating slot 49, and a handle flange 48 for positioning the same provide a means for shutting off or permitting the light to fall upon the chart board, while allowing the light rays 43 to reach the instrument board continuously.

It has been found that utilizing a Nicol prism, as at 40, substantially reduces reflection or glare from the instruments on the instrument board 12, and at the same time prevents reflections of the instrument board on the windshield 50. The plane of polarization is rotated until the reflection is at a minimum, thus making it easier for the pilot to read his instruments more accurately without being bothered by reflection or glare in his eyes. At the same time by utilizing the control flange 48 of the shutter 47 he controls the amount of light reaching the chart board when the same is needed and may cut it off entirely when it is not needed without interfering with the use of the light on the instrument board and without the necessity of using additional lighting means therefor.

Other modifications and changes in the proportions and arrangements of the parts may be made by those skilled in the art without departing from the nature and scope of the invention, as defined in the appended claims.

The invention described herein may be manufactured and used by or for the Government of the United States of America for governmental

purposes without the payment of any royalties thereon or therefor.

Having thus set forth and disclosed the nature of this invention, what is claimed is:

- 5 1. In a light fixture for a cockpit and instrument board of an airplane, means for universally mounting the light fixture to the side of the cockpit, means for directing light rays from the lamp in the light fixture to the instrument board, and 10 shutter means for directing and cutting off other light rays from the same lamp in the lighting fixture to the cockpit, said first mentioned light directing means including a Nicol prism for polarizing the light rays to the instrument

board, said Nicol prism being rotatable on the lens axis.

2. In a light fixture for a cockpit and instrument board of an airplane, means for universally mounting the light fixture to the side of the cockpit, means for directing light rays from the lamp in the light fixture to the instrument board, and shutter means for directing and cutting off other light rays from the same lamp in the lighting fixture to the cockpit, said first mentioned light directing means including a Nicol prism for polarizing the light rays to the instrument board.

JOHN M. ROPER.
